UNITED STATES PATENT OFFICE.

GEORGE HARE FORD, OF NEW HAVEN, CONNECTICUT.

DESIGN FOR A COFFIN-PLATE.

SPECIFICATION forming part of Design No. 27,843, dated November 9, 1897.

Application filed September 10, 1897. Serial No. 651,258. Term of patent 7 years.

To all whom it may concern:

Be it known that I, GEORGE HARE FORD, a citizen of the United States, residing at New Haven, in the county of New Haven and State of Connecticut, have invented a new and useful Design for Coffin-Plates and Similar Articles, of which the following is a specification.

The drawing hereto annexed shows a coffin-plate embodying my design, and the essential features thereof are the substantially rectangular panel A, presenting an unornamented effect and having at the top and bottom a line of plain curved molding B B, and beyond that a line of ornamented molding C C, the sides of the panel being inclosed by

curved and foliated ornaments D D. Below the bottom line or ornamented molding is a plain base E, slightly longer than the panel A, and the whole is surmounted by the conventional Egyptian representation of out-stretched wings.

What I claim, and desire to secure by Letters Patent, is—

The design for coffin-plates and similar articles substantially as herein shown and described.

GEORGE HARE FORD.
